CUP BRUSH

Brooks E. Nelson, Chagrin Falls, Ohio, assignor to The Osborn Manufacturing Company, Cleveland, Ohio, a corporation of Ohio

Application October 26, 1953, Serial No. 388,335

6 Claims. (Cl. 15—180)

This invention relates as indicated to a cup brush, and more particularly to a rotary brush of the twisted tuft type adapted to be mounted on a spindle or the like and driven at relatively high speeds. Reference may be had to Bickel et al. Patent No. 2,062,047 and to Peterson Patent No. 2,480,877 for examples of brushes of this general type.

Rotary brushes and more particularly cup brushes of the coil knot or twisted tuft type in which the brush material comprises a series of twisted tufts formed by doubling and then twisting a bundle of stranded brush material, usually wire, serve a wide variety of purposes and are commonly employed when a relatively harsh brushing action is desired as for the removal of excess weld metal, mill scale, etc. Inasmuch as the twisted tufts extend generally parallel to the axis of the tool, they are especially subject to the action of centrifugal force in use, and there is a resultant tendency for the brush to become distorted from its original shape. This tendency is, of course, accentuated when the brush is pressed forcibly against the work. When the bristle tufts are held within a cup having side walls which flare outwardly at a considerable angle this difficulty is minimized since the tufts likewise have an initial flare but, on the other hand, the brushing action then obtained is not as effective as desired for certain types of work. A straight-sided cup would accordingly often be preferable, but has not proven satisfactory in the past for the reason that the resultant brush quickly got out of balance. These brushes ordinarily comprise an inner and outer ring of tufts, and under the influence of centrifugal force tufts of the inner series would tend to swing radially outwardly with pairs of such tufts often forcing themselves in between tufts of the outer series, thereby producing an irregular brushing surface and putting the tool out of balance. As in the case of any high speed rotary tool, proper balance is, of course, essential, since otherwise a violent wobbling effect will be obtained.

It is accordingly a principal object of my invention to provide a cup brush in which the brush material extends generally parallel to the axis of rotation of the tool and in which the inner portion of the brush material is constrained from interposing itself into the outer portion of such material to produce unbalance and uneven brushing action.

Another object is to provide a novel cup brush wherein the various elements are assembled together in a simple but strong manner to enable the brush material to resist both outward flaring action under the influence of centrifugal force and also pressure when the tool is held forcibly against the work.

Other objects of the invention will appear as the description proceeds.

To the accomplishment of the foregoing and related ends, said invention then comprises the features herein-after fully described and particularly pointed out in the claims, the following description and the annexed drawing setting forth in detail certain illustrative embodiments of the invention, these being indicative, however, of but a few of the various ways in which the principle of the invention may be employed.

2

In said annexed drawing:

Fig. 1 is a diametrical transverse section through a brush embodying my invention;

Fig. 2 is a perspective view of an inner cup element employed in the assembly; and

Fig. 3 is a plan view of an annular disc or washer to which twisted tufts of brush material are secured.

Referring now more particularly to said drawing, the embodiment of my invention illustrated therein comprises an annular cup-shaped holder 1 which seats and encloses the brush material and also serves as the means for securing the entire assembly together. Seated in the bottom of such cup is a flat annular ring or washer 2 having a plurality of small holes 3 therethrough adjacent its outer periphery. The edges of such holes are rounded, and a bundle of brush bristle material (ordinarily wire) is passed through each hole and twisted upon itself to form the twisted tufts 4. The base of cup 1 is bulged or deformed at 5 to provide a shallow annular channel adapted to receive the rebent portions of such tufts when ring 2 is seated therein as shown in Fig. 1.

A second inner cup 6 (Fig. 2) in the form of a thin sheet metal stamping is next seated within cup 1, the sides of such cup 6 being dimensioned closely to engage the inner sides of the row of tufts 4 and having an inner opening 7 of the same diameter as the inner opening 8 of ring 2 similarly to fit the central cylindrical portion 9 of cup 1. It will thus be seen that the outer row of tufts 4 is in effect retained within a rather deep annular channel defined by the walls of cups 1 and 6 respectively. The side wall of cup 6 is dimensioned to extend to a point substantially equal to that of the side wall of cup 1 and will desirably slope slightly radially outwardly. The outer lip 10 of cup 1 may also desirably be slightly flared, but the side of the cup itself is preferably substantially parallel to the axis of rotation of the tool.

A small spacer washer 11 is next inserted followed by ring 12 generally similar to ring 2 but of a smaller diameter to fit within cup 6 as shown and provided with a similar series of twisted bristle tufts 13. A slightly dished washer 14 is then installed adapted to engage the inner side of the ring of tufts 13 to hold the same in the general position illustrated in Fig. 1. Of course, when the tool is mounted upon a spindle and rapidly rotated, such tufts tend to swing radially outwardly. The inner end portion 15 of the inner cylindrical hub 9 of cup 1 may now be upset as shown to clamp the above-described components together as a permanent assembly.

When the tool is placed in operation, it will be seen that the outer ring of tufts 4, being retained within the relatively deep annular channel defined between cups 1 and 6, will not tend to flare outwardly unduly under the action of centrifugal force. Furthermore, the inner ring, of tufts 13 is supported by cup 6 against like outwardly flaring movement and even more important, two or more such tufts 13 are prevented from becoming interposed between two adjacent tufts 4 and throwing the tool out of balance. I have accordingly provided a high speed rotary tool utilizing twisted tuft brush material in which such tufts are constrained to extend generally parallel to the axis of rotation of the tool for desired brushing action and which will remain in balance even under severe working conditions. The lip of inner cup 6 may become slightly undulating due to the pressure of the tufts thereagainst, but this will merely serve more positively to retain the latter in desired symmetrical relationship.

As shown in Fig. 1, the inner and outer series of tufts will generally extend an equal distance from the cup-shaped holder, and the lip of the inner cup will encircle the inner series of tufts in the general region defined by the lip of such holder. Such inner cup may, however,

3

extend somewhat further if desired. The two cups in effect define an annular channel from which the outer series of tufts extend and such outer series is accordingly better supported and maintained in proper position when the tool is held forcibly against the work;

The inner surface of the central cylindrical portion 9 may be threaded for direct attachment to a spindle or the like, or it may be of hexagonal or other non-circular contour for mounting on a complementary spindle.

Other modes of applying the principle of the invention may be employed, change being made as regards the details described, provided the features stated in any of the following claims or the equivalent of such be employed.

I therefore particularly point out and distinctly claim as my invention:

1. A cup brush comprising a cup-shaped annular sheet metal holder having a generally cylindrical outer wall and an internal cylindrical wall portion of less axial extent defining therebetween an annular channel in which the other brush elements are adapted to be seated and retained, the lip of said outer wall flaring outwardly, an annular flat disc seated in such annular channel and fitting said internal wall portion, said disc having a plurality of closely spaced evenly distributed holes therethrough adjacent its outer periphery, tufts of wire bristle material inserted through such holes and doubled and twisted on themselves about the edge of the disc to form twisted tufts extending a substantial distance beyond said lip in a direction substantially parallel to the axis of the brush, an inner thin sheet metal cup tightly fitted against said disc and the inner sides of said tufts having a central opening fitting said internal wall portion of said outer holder, the side wall of said inner cup flaring slightly outwardly and extending substantially the same distance as said outer wall toward the working ends of said tufts, a spacer washer fitting said internal wall portion and engaging the bottom of said inner cup but spaced from the side wall of the latter, a second disc engaging said washer and fitting said internal wall portion bearing an inner circumferential series of twisted tufts of brush bristle material in the same manner as said first disc, said inner series of tufts extending generally parallel to the axis of the brush and supported against the inner face of the side wall of said inner cup, and a dished washer fitting said internal wall portion and engaging said second disc with its outer periphery bearing against said inner series of tufts, the end of said internal cylindrical wall portion being deformed to engage said latter washer firmly to secure the entire assembly together as a unit and the base of said holder being bulged adjacent its outer periphery better to accommodate the rebent portions of said twisted tufts of said first disc.

2. A cup brush comprising a cup-shaped annular sheet metal holder having a generally cylindrical outer wall and an internal cylindrical wall portion of less axial extent defining therebetween an annular channel in which the other brush elements are adapted to be seated and retained, an annular flat disc seated in such annular channel and fitting said internal wall portion, said disc having a plurality of closely spaced evenly distributed holes therethrough adjacent its outer periphery, tufts of wire bristle material inserted through such holes and doubled and twisted on themselves about the edge of the disc to form twisted tufts extending a substantial distance beyond said lip in a direction substantially parallel to the axis of the brush, an inner thin sheet metal cup tightly fitted against said disc and the inner sides of said tufts having a central opening fitting said internal wall portion of said outer holder, a spacer washer fitting said internal wall portion and engaging the bottom of said inner cup but spaced from the side wall of the latter, a second disc engaging said washer and fitting said internal wall portion bearing an inner circumferential series of twisted tufts.

of brush bristle material in the same manner as said first disc, said inner series of tufts extending generally parallel to the axis of the brush and supported against the inner face of the side wall of said inner cup, a dished washer fitting said internal wall portion and engaging said second disc with its outer periphery bearing against said inner series of tufts, and means securing such assembly tightly together as a unit.

3. A cup brush comprising a cup-shaped annular holder having a generally cylindrical outer wall and an internal cylindrical wall portion of less axial extent defining therebetween an annular channel in which the other brush elements are adapted to be seated and retained, an annular flat disc seated in such annular channel and fitting said internal wall portion, tufts of brush material secured to said disc and extending a substantial distance beyond said outer wall in a direction substantially parallel to the axis of the brush, an inner thin sheet metal cup tightly fitted against said disc and the inner sides of said tufts having a central opening fitting said internal wall portion of said outer holder, a second disc fitting said internal wall portion having tufts of brush material secured thereto and extending therefrom forming an inner series of tufts supported against the inner face of the side wall of said inner cup, means internally of said inner series engaging and bracing the same against inward movement, and means securing such assembly tightly together as a unit.

4. In a rotary brush having twisted tufts of brush material extending generally parallel to the axis of rotation of said brush and arranged in two closely adjacent concentric inner and outer circles, and an outer annulus closely surrounding said outer circle of tufts to prevent radially outward swinging movement of said tufts under the influence of centrifugal force in operation; another annulus interposed between said circles of tufts and closely surrounding said inner circle in a region at least as near the working ends of said tufts as said outer annulus to prevent excessive outward movement of said tufts of said inner circle between said tufts of said outer circle when the brush is rotated at high speeds in use.

5. In a cup brush comprising a cup-shaped outer holder having a generally cylindrical outer wall, an outer circle of twisted tufts of brush material secured therein and extending a substantial distance beyond said outer wall, and an inner circle of twisted tufts of brush material secured in said holder within said first circle and extending a substantially equal distance generally parallel to the axis of the brush and said tufts of said outer circle; an annulus interposed and secured between said circles of tufts and enclosing said inner circle effective to prevent excessive outward movement of the tufts of said inner circle under the influence of centrifugal force when the brush is rotated at high speeds in use.

55 6. In a rotary brush having an outer circle of brush
material extending generally parallel to the axis of rotation
of said brush, an outer annular member closely encircling and embracing said circle of brush material to
inhibit radially outwardly flaring movement thereof under
60 the influence of centrifugal force when said brush is
rotated rapidly, and an inner concentric circle of brush
material extending parallel to that of said outer circle
and closely adjacent thereto; an annular element inter-
posed between said circles of brush material and embrac-
65 ing said inner circle to inhibit outward flaring movement
of said brush material of said inner circle into the region
of said outer circle under the influence of centrifugal
force.
